UNITED STATES PATENT OFFICE.

PAUL WILMER JONES, OF MOBILE, ALABAMA, ASSIGNOR OF ONE-THIRD TO GLENN L. NORMAN AND ONE-THIRD TO EUGENE WALTERS.

LIQUID-FUEL BURNER.

Application filed June 15, 1923. Serial No. 645,660.

To all whom it may concern:

Be it known that I, PAUL W. JONES, a citizen of the United States, residing at Mobile, in the county of Mobile and State of Alabama, have invented certain new and useful Improvements in Liquid-Fuel Burners, of which the following is a specification, reference being had therein to the accompanying drawings.

10 This invention relates to liquid fuel burners and it has for its object to provide an improved device of this character constructed in such manner that complete combustion of the fuel will be attained and all of the heat 15 units will be conserved and utilized with a consequent efficiency resulting in a marked improvement in this art.

Further objects and advantages of the invention will be set forth in the detailed description which follows.

In the accompanying drawings:

Fig. 1 is a side elevation of a burner and heat retainer adapted to be placed in the fire-box of a coal stove;

25 Fig. 2 is a vertical sectional view therethrough;

Fig. 3 is a transverse vertical sectional view therethrough on line 3-3 of Fig. 2;

30 Fig. 4 is a sectional view through a fuel supply and vaporizing pipe at the entrance end of said pipe.

Fig. 5 is a side elevation illustrating a modified form of the invention;

25 Fig. 6 is a longitudinal sectional view through the form of the invention illustrated in Fig. 5; and

Fig. 7 is a transverse sectional view upon line 7-7 of Fig. 6.

Like numerals designate corresponding parts in all of the figures of the drawings.

The form of the invention illustrated in Figs. 1 to 4, inclusive is one particularly adapted for domestic use and intended for use in the fire-boxes of coal stoves. I am 45 aware of the fact that many oil burners have been devised for use in the fire-boxes of coal stoves. However, in such devices of that character as have come into general use the jet of flame merely strikes a flame spreader of metal which is usually of comparatively small size, after which there is nothing to prevent the escape of the products of combustion through the flue to the chimney. Thus a large percentage of the products of 50 combustion are wasted and lost and very

little efficiency is had. It is a primary object of the present invention to direct the jets of flame and the products of combustion into flues formed directly in relatively large bodies of refractory and heat resistant material, such as fire clay, for example, and which bodies are of honeycomb structure and the cells of which intersect the channels constituting the flues through said refractory bodies.

60 By virtue of this arrangement the whole mass ultimately becomes incandescent and presents a white hot mass so that the vapors discharged thereinto from the nozzles or jets of the burners are completely consumed and 65 the heat is conserved and multiplied over what would be the case with burners of ordinary construction.

In the drawing 5 designates a mass of refractory material highly resistant to heat 75 and which for purposes of convenience and illustration has here been illustrated as of cellular checker work construction. However, it is to be understood that the particular direction and arrangement of the cells 80 is immaterial so long as the block 5 is of cellular construction. Formed within the block 5 are the sinuous channels 6 which intersect the passages 7 formed by the cellular construction of the block. Thus air may 85 enter the block from all directions and mix with the products of combustion in the sinuous passages 6 with the result that perfect combustion of the gases is brought about and the whole mass soon becomes white hot.

90 The fuel, which may be any suitable fuel oil but is preferably kerosene is supplied from a pipe 8 through a controlling needle valve 9, to a vaporizing pipe 10 which overlies the block 5. The block 5 is provided 95 with a cavity 11, said cavity being lined with a plurality of asbestos sheets 11^a and this cavity serves to receive, initially, a small amount of oil which when lighted heats the vaporizing pipe 10 and a core 12 which is 100 located in said pipe. The core is grooved or channeled for a short distance at its entrance end as indicated at 12^a, see Fig. 4, and the core is smaller than pipe 10 so that the oil is spread out in a relatively thin film and this coupled with the fact that the core 12 itself presents a heat retaining mass, results in rapidly vaporizing the oil and supplying 105 an initial vapor to the jets 13 and 14 which discharge into the lower end of the sinuous 110

passages 6. These jets or nozzles are carried by a horizontal length of pipe 15 which is connected with the pipe 10 by a vertical leg 16. This vertical leg may lie outside of the 5 block proper or it may be embedded therein.

It is to be understood that the passages 6 may be of any desired formation. I have shown them as having relatively sharp bends but it is within the purview of the invention to make these bends more or less in 10 number and of any desired inclination. The bottom of the block 5 is preferably closed and solid, as indicated at 5^b.

In the form of the invention illustrated 15 in Figs. 5 to 7, the block 5^b is of the same general formation as that previously described but in this case the structure is particularly intended for use in steam boilers, such as stationary boilers, locomotive 20 boilers, steam ship boilers and the like and in this construction the sinuous passages 6^a, 6^b extend in a general direction longitudinally of the block instead of vertically as in the previous case. In this case the vaporizing 25 pipe 10^a is given a return bend over the block and its vertical leg 10^b is provided with the nozzles 20, 20^a which discharge into the sinuous passages 6^a, 6^b, respectively. Otherwise the construction is the same 30 as that previously described. However, since, in the case of steam ship and locomotive boilers the structure is subjected to considerable vibration, I prefer to embed in the block 5^a some suitable strengthening and 35 binding material, such as asbestos or the like, indicated at 21 and which aids in preventing cracking and disintegration of the block 5^a.

By virtue of the construction illustrated 40 in Fig. 4 the vaporizer, when it once becomes hot holds a maximum degree of heat under a low flame, thus getting a complete vaporization of the oil used and avoiding waste of oil in the burning of a partly 45 vaporized gas. But combustion does not take place in the sinuous passages alone but takes place in all of the comparatively small cells into which any of the gas finds its way and just enough air is drawn into the sides of 50 the structure to supply any deficiency which may exist. By reason of the combustion taking place, as stated, over a large part of the body constituted by the block 5, the heating of said body to an incandescent 55 mass is rapidly brought about and the firebox or combustion chamber of the stove or boiler is correspondingly heated and this without any waste of the oil.

It is to be understood that the invention 60 contemplates making all or any part of the sides of the block 5 open. I have shown the bottom closed and it is manifest that any one of the sides may be correspondingly closed.

65 While I have shown only two jets in Fig.

5, it is manifest that these may be multiplied to any desired extent without departure from the invention. In this form of the invention I prefer to leave out or omit the core 12 because when using the invention 70 in steam boilers, crude oil is generally used as the fuel and this is too thick to pass through the structure illustrated in Fig. 4.

I further contemplate installing in cellular fire clay or like refractory blocks of 75 this character electric heating elements adapted to bring said blocks to an incandescent state and it is to be understood that the invention includes this idea.

When the combustion chamber and the heat retainer and the multiplier constituted by the block 5 once becomes thoroughly hot, the intake of air drawn in through the various holes throughout the hot burner results in immediately heating the air to 80 such a degree of heat that it mixes perfectly with the flame, vapor and carbon that has formerly been going to waste. Mixing of the hot air with the inclosed flame forms a 85 perfect gas and is 100% combustible. It is 90 further to be understood that the invention contemplates any shape or arrangement of vaporizer type, for many ways of initially heating the oil to form a combustible gas will readily suggest themselves to those 95 skilled in the art.

The burner of this invention is so efficient in operation that it effects practically 100% combustion of oil consumed. Consequently 100 the formation and accumulation of carbon, soot, smoke, etc. is prevented and the interior walls of the firebox and the flues are left clear of unburnt substances which would otherwise cut down the conductivity of these parts with consequent reduction in 105 efficiency. All of the heat created by the burner is permitted to come into direct contact with the parts intended to be heated and increased efficiency in the generation of steam is the result. This effects a great 110 saving in the combustion of fuel. Furthermore it eliminates the cost of blowing out and cleaning the flues which is ordinarily quite an item of expense.

Referring now to Figs. 5 and 6, 30 115 designates a controlling needle valve by which the flow of fuel into the overhead generating pipe is controlled. Furthermore, each of the jets 20, 20^a is provided with an individual controlling valve 20^b, 20^c, 120 respectively, so that any desired intensity of flame may be maintained locally at the said jets. This provides a double control of the oil and flame in that the valve 30 provides one controlling means and the valves 20^b, 20^c 125 provide a second controlling means.

It is not to be understood that the asbestos rope 21 extends around the outside of the blocks, only. It not only extends around the outside of the block but is inserted in 130

the material of the block in such manner that each cell is reenforced. This is indicated by the dotted sinuous lines 31 in Fig. 6 and the transversely extending strands 32 5 in Fig. 7.

Having described my invention what I claim is:

1. A burner of the character described comprising an integral cellular mass of refractory material adapted to be seated as a unit in a fire box, said mass having a closed bottom and having some of its cellular structure omitted to form sinuous passages which are in addition to the openings of the cells, 10 a fuel supply pipe, a vaporizer for the fuel supply pipe which extends across said cellular mass and nozzles carried by said fuel supply pipe and discharging directly into 15 the entrance ends of the sinuous passages.

2. A burner of the character described comprising an integral cellular mass of refractory material adapted to be seated as a unit in a fire box, said mass having a closed bottom and having some of its cellular structure omitted to form sinuous passages which are in addition to the openings of the cells, 20 a fuel supply pipe, a vaporizer for the fuel supply pipe which extends across said cellular mass and nozzles carried by said fuel supply pipe and discharging directly into 25 the entrance ends of the sinuous passages, 30 said cellular mass having a concave recess formed in its upper portion over which the vaporizer extends.

In testimony whereof I hereunto affix my signature.

PAUL WILMER JONES.
